UNITED STATES PATENT OFFICE.

MAX CONRAD, OF ASCHAFFENBURG, GERMANY, ASSIGNOR TO THE FIRM OF E. MERCK, OF DARMSTADT, GERMANY.

PROCESS OF MAKING DIALKYL BARBITURIC ACID.

No. 893,308.

Specification of Letters Patent.

Patented July 14, 1908.

Application filed November 8, 1904. Serial No. 231,871.

To all whom it may concern:

Be it known that I, MAX CONRAD, a subject of the Emperor of Germany, residing at Aschaffenburg, in the Empire of Germany, have invented certain new and useful Improvements in the Processes of Manufacturing Dialkyl Malonylamid Compounds and Dialkyl Barbituric Acids. Therefrom, of which the following is a description.

10 My invention relates to the manufacture of dialkyl-malonylamid compounds and dialkyl-barbituric acids therefrom, and it consists of certain novel processes particularly pointed out in the concluding claims.

15 According to experiments made by Emil Fisher and Alfred Dilthey (*Berlin Reports* 35 (1902, page 844) the dialkylmalonamids and the dialkylmalonamin acid ester can not practically be obtained from dialkylmalon-20 acid esters and also that the ammonium salts of the dialkylmalonamids can not be converted into amids. According to the above authorities the only way to accomplish the result sought is by means of the acid chlorides. 25 I have discovered, however, a convenient and smooth method of manufacturing dialkylmalonylamid compounds. This method consists in moderately heating the cyandialkylacet amids, the cyandialkylacetylurea, 30 and the cyandialkylacetic ester, with concentrated acids. These dialkylmalonylamid compounds can be converted in the same manner as the dialkylmalonacidester with urea, guanidin or thiourea into dialkylbarbi-35 turic-acids, under the action of the same condensing means, viz., the alcoholates of alkali- or earthy metals, the metals themselves or the amids thereof.

40 I will now describe the manner in which I at present prefer to practice my invention, giving, by way of illustration, a number of examples thereof, but it will be understood that various modifications and changes, both as to materials and treatment, may be made 45 without departing from the spirit of my invention and without exceeding the scope of my claim.

First example.—If one part of the cyandethylacetamid, which melts at 121°, is heated 50 in the water bath for one hour with 5 to 10 parts of concentrated sulfuric acid, to which are added preferably one or two parts of water, and if then the solution is poured out into the water, diethylmalonylamid is separated in crystals. This may be easily puri-

fied by dissolving it in boiling water. It can be sublimated and melts at 220° (uncorr.).

Second example.—In the same manner from the cyandipropylacetamid, which melts at 153°, the dipropylmalonamid, which melts 60 at 214°, is obtained.

Third example.—The cyandibenzylacetamid, which melts at 165°, produces, under the same conditions, the dibenzylmalonylamid, which melts at 197°.

Fourth example.—From the cyandiethylacetic ester, the diethylmalonaminacid ester

70 is obtained in colorless prisms, which melt at 79° and can be easily dissolved, especially with warmth, in ether, spirit, acetic ether and benzol. The R in the last formula means an alkyl group such as methyl, ethyl, etc. The ester boils to a large extent at 263° (uncorr.). In order to obtain diethylbarbituric acid therefrom, 60 grams of sodium are dissolved in 4 liters of absolute alcohol and to this hot solution 200 grams of urea and 470 75 grams of ester are added. The mixture is heated for several hours in the water bath and the alcohol is then removed by distillation. The solid residue is dissolved in water and is decomposed with acetic acid or hydro-85 chloric acid. In this way 210 grams of diethylbarbituric acid are obtained.

Fifth example.—From cyandipropylacetic ester, the dipropylmalonaminacidester is obtained of the melting point 91° (uncorr.). If 90 this ester is treated (in the manner described in the fourth example) with urea and sodium alcoholate, dipropylbarbituric acid is obtained of the melting point 145° (corr.).

Sixth example.—From an alcoholic solution of 60 grams of sodium, 200 grams of thiourea and 470 grams of diethylmalonaminacidester, with the same treatment, 350 grams of diethylmalonylthiourea are obtained. The same melts at 175° C. and can 100 be easily converted into diethylbarbituric acid by oxidizing means, or by means of metallic oxid, as lead-oxid.

Seventh example.—A solution of 120 grams of sodium, 240 grams of guandinhydrochlorate and 470 grams of diethylmalonaminacidester furnishes under the same conditions 250 grams of diethyl-malonylguanidin. This crystallizes in colorless needles, which decompose at temperatures of over 110

300° C. without melting. The compound can be dissolved in diluted acids and in excess of ammonia with warmth. By being heated with diluted acids it is converted, while separating ammonia, into dialkylbarbituric acids. From 46 grams of sodium, 120 grams of guanidin and 570 grams of diethylmalonaminacidester under the same conditions the diethylmalonylguanidin may be obtained for conversion into dialkylbarbituric acid as above described.

10 Eighth example.—If a solution of 10 parts of cyandiethylacetylurea is heated with about 16 to 20 parts of concentrated nitric acid in the water bath for about an hour, diethylmalonuracidamid,

20 is separated when water is added, which product can be easily purified by shaking it with diluted ammonia and dissolving it in hot water. It melts at 199°.

The specific process hereinabove described 25 employing thiourea while generically claimed herein is specifically the subject of a separate application, No. 326038 filed July 13, 1906.

Having thus fully described my invention, what I claim and desire to secure by Letters 30 Patent is:

1. The process of manufacturing a dialkylbarbituric acid which consists in first treating a cyandialkylacetic compound with a concentrated acid, then condensing the re-

sulting dialkylmalonylamid compound with 35 derivative of urea to a dialkylbarbituric acid compound and then converting the latter into a dialkylbarbituric acid.

2. In the process of manufacturing dialkylbarbituric acid the step which consists in 40 converting a cyandialkylacetic compound to a dialkylmalonylamid compound by treating with a concentrated acid.

3. In the process of manufacturing dialkylbarbituric acid the step which consists in 45 converting cyandiethyl acetic ester to diethylmalonamin acid ester by treating with concentrated sulfuric acid.

4. In the process of manufacturing dialkylbarbituric acid the step which consists in 50 condensing a dialkylmalonylamid compound with a derivative of urea to a dialkylbarbituric acid compound and then converting the latter into a dialkylbarbituric acid.

5. In the process of manufacturing dialkylbarbituric acid the step which consists in 55 condensing diethylmalonaminacid ester with guanidin to imino-diethylbarbituric acid and then converting the latter into diethylbarbituric acid by saponification.

In testimony whereof I hereunto sign my name to this specification in the presence of two subscribing witnesses,

MAX CONRAD.

Witnesses:

JEAN GRUND,
CARL GRUND.
